(57) **CLAIM**

The ornamental design for parts for a toy construction set, as shown and described.

DESCRIPTION

FIG. 1.1 is a left side view of a first part for a toy construction set;

FIG. 1.2 is a bottom view of a first part for a toy construction set;

FIG. 1.3 is a top view of a first part for a toy construction set; FIG. 1.4 is a front view of a first part for a toy construction set;

FIG. 1.5 is a perspective view of a first part for a toy construction set;

FIG. 1.6 is a right side view of a first part for a toy construction set;

FIG. 1.7 is a perspective view of a first part for a toy construction set; and

FIG. 1.8 is a bottom view of a first part for a toy construction set.

FIG. 2.1 is a perspective view of a second part for a toy construction set;

FIG. 2.2 is a left side view of a second part for a toy construction set;

FIG. 2.3 is a bottom view of a second part for a toy construction set;

FIG. 2.4 is a front view of a second part for a toy construction set;

FIG. 2.5 is a right side view of a second part for a toy construction set;

FIG. 2.6 is a perspective view of a second part for a toy construction set;

FIG. 2.7 is a top view of a second part for a toy construction set; and

FIG. 2.8 is a rear view of a second part for a toy construction set.

FIG. 3.1 is a perspective view of a third part for a toy construction set;

FIG. 3.2 is a front view of a third part for a toy construction set;

FIG. 3.3 is a top view of a third part for a toy construction set;

FIG. 3.4 is a bottom view of a third part for a toy construction set;

FIG. 3.5 is a left side view of a third part for a toy construction set;

FIG. 3.6 is a rear view of a third part for a toy construction set;

FIG. 3.7 is a right side view of a third part for a toy construction set; and

(Continued)

FIG. 3.8 is a perspective view of a third part for a toy construction set.

FIG. 4.1 is a perspective view of a fourth part for a toy construction set;

FIG. 4.2 is a front view of a fourth part for a toy construction set;

FIG. 4.3 is a top view of a fourth part for a toy construction set;

FIG. 4.4 is a left side view of a fourth part for a toy construction set;

FIG. 4.5 is a right side view of a fourth part for a toy construction set;

FIG. 4.6 is a rear view of a fourth part for a toy construction set;

FIG. 4.7 is a side view of a fourth part for a toy construction set; and

FIG. 4.8 is a perspective view of a fourth part for a toy construction set.

FIG. 5.1 is a perspective view of a fifth part for a toy construction set;

FIG. 5.2 is a front view of a fifth part for a toy construction set;

FIG. 5.3 is a top view of a fifth part for a toy construction set;

FIG. 5.4 is a rear view of a fifth part for a toy construction set;

FIG. 5.5 is a bottom view of a fifth part for a toy construction set;

FIG. 5.6 is a right side view of a fifth part for a toy construction set;

FIG. 5.7 is a left side view of a fifth part for a toy construction set; and

FIG. 5.8 is a perspective view of a fifth part for a toy construction set.

FIG. 6.1 is a perspective view of a sixth part for a toy construction set;

FIG. 6.2 is a top view of a sixth part for a toy construction set;

FIG. 6.3 is a bottom view of a sixth part for a toy construction set;

FIG. 6.4 is a left view of a sixth part for a toy construction set;

FIG. 6.5 is a rear view of a sixth part for a toy construction set;

FIG. 6.6 is a front view of a sixth part for a toy construction set;

FIG. 6.7 is a right side view of a sixth part for a toy construction set; and

FIG. 6.8 is a perspective view of a sixth part for a toy construction set.

FIG. 7.1 is a perspective view of a seventh part for a toy construction set;

FIG. 7.2 is a top view of a seventh part for a toy construction set;

FIG. 7.3 is a left side view of a seventh part for a toy construction set;

FIG. 7.4 is a bottom view of a seventh part for a toy construction set;

FIG. 7.5 is a front view of a seventh part for a toy construction set;

FIG. 7.6 is a rear view of a seventh part for a toy construction set;

FIG. 7.7 is a right side view of a seventh part for a toy construction set; and

FIG. 7.8 is a perspective view of a seventh part for a toy construction set.

FIG. 8.1 is a perspective view of an eighth part for a toy construction set;

FIG. 8.2 is a front view of an eighth part for a toy construction set;

FIG. 8.3 is a rear view of an eighth part for a toy construction set;

FIG. 8.4 is a bottom view of an eighth part for a toy construction set;

FIG. 8.5 is a top view of an eighth part for a toy construction set;

FIG. 8.6 is a left side view of an eighth part for a toy construction set;

FIG. 8.7 is a right side view of an eighth part for a toy construction set; and

FIG. 8.8 is a perspective view of an eighth part for a toy construction set.

FIG. 9.1 is a perspective view of a ninth part for a toy construction set;

FIG. 9.2 is a front view of a ninth part for a toy construction set;

FIG. 9.3 is a rear view of a ninth part for a toy construction set;

FIG. 9.4 is a top view of a ninth part for a toy construction set;

FIG. 9.5 is a right side view of a ninth part for a toy construction set;

FIG. 9.6 is a bottom view of a ninth part for a toy construction set;

FIG. 9.7 is a left side view of a ninth part for a toy construction set; and

FIG. 9.8 is a perspective view of a ninth part for a toy construction set.

FIG. 10.1 is a perspective view of a tenth part for a toy construction set;

FIG. 10.2 is a rear view of a tenth part for a toy construction set;

FIG. 10.3 is a front view of a tenth part for a toy construction set;

FIG. 10.4 is a top view of a tenth part for a toy construction set;

FIG. 10.5 is a left side view of a tenth part for a toy construction set;

FIG. 10.6 is a bottom view of a tenth part for a toy construction set;

FIG. 10.7 is a right side view of a tenth part for a toy construction set; and

FIG. 10.8 is a perspective view of a tenth part for a toy construction set.

FIG. 11.1 is a perspective view of an eleventh part for a toy construction set;

FIG. 11.2 is a left side view of an eleventh part for a toy construction set;

FIG. 11.3 is a top view of an eleventh part for a toy construction set;

FIG. 11.4 is a bottom view of an eleventh part for a toy construction set;

FIG. 11.5 is a front view of an eleventh part for a toy construction set;

FIG. 11.6 is a rear view of an eleventh part for a toy construction set;

FIG. 11.7 is a right side view of an eleventh part for a toy construction set; and

FIG. 11.8 is a perspective view of an eleventh part for a toy construction set.

FIG. 12.1 is a perspective view of a twelfth part for a toy construction set;

FIG. 12.2 is a left side view of a twelfth part for a toy construction set;

FIG. 12.3 is a top view of a twelfth part for a toy construction set;

FIG. 12.4 is a bottom view of a twelfth part for a toy construction set;

FIG. 12.5 is a front view of a twelfth part for a toy construction set;

FIG. 12.6 is a rear view of a twelfth part for a toy construction set;

FIG. 12.7 is a right side view of a twelfth part for a toy construction set; and

FIG. 12.8 is a perspective view of a twelfth part for a toy construction set.

FIG. 13.1 is a perspective view of a thirteenth part for a toy construction set;

FIG. 13.2 is a left side view of a thirteenth part for a toy construction set;

FIG. 13.3 is a top view of a thirteenth part for a toy construction set;

FIG. 13.4 is a bottom view of a thirteenth part for a toy construction set;

FIG. 13.5 is a front view of a thirteenth part for a toy construction set;

FIG. 13.6 is a rear view of a thirteenth part for a toy construction set;

FIG. 13.7 is a right side view of a thirteenth part for a toy construction set; and

FIG. 13.8 is a perspective view of a thirteenth part for a toy construction set.

FIG. 14.1 is a perspective view of a fourteenth part for a toy construction set;

FIG. 14.2 is a top view of a fourteenth part for a toy construction set;

FIG. 14.3 is a left side view of a fourteenth part for a toy construction set;

FIG. 14.4 is a bottom view of a fourteenth part for a toy construction set;

FIG. 14.5 is a front view of a fourteenth part for a toy construction set;

FIG. 14.6 is a back view of a fourteenth part for a toy construction set;

FIG. 14.7 is a right side view of a fourteenth part for a toy construction set; and

FIG. 14.8 is a perspective view of a fourteenth part for a toy construction set.

FIG. 15.1 is a perspective view of a fifteenth part for a toy construction set;

FIG. 15.2 is a front view of a fifteenth part for a toy construction set;

FIG. 15.3 is a bottom view of a fifteenth part for a toy construction set;

FIG. 15.4 is a rear view of a fifteenth part for a toy construction set;

FIG. 15.5 is a top view of a fifteenth part for a toy construction set;

FIG. 15.6 is a left side view of a fifteenth part for a toy construction set;

FIG. 15.7 is a right side view of a fifteenth part for a toy construction set; and

FIG. 15.8 is a perspective view of a fifteenth part for a toy construction set.

FIG. 16.1 is a perspective view of a sixteenth part for a toy construction set;

FIG. 16.2 is a front view of a sixteenth part for a toy construction set;

FIG. 16.3 is a rear view of a sixteenth part for a toy construction set;

FIG. 16.4 is a left side view of a sixteenth part for a toy construction set;

FIG. 16.5 is a top view of a sixteenth part for a toy construction set;

FIG. 16.6 is a right side view of a sixteenth part for a toy construction set;

FIG. 16.7 is a bottom view of a sixteenth part for a toy construction set; and

FIG. 16.8 is a perspective view of a sixteenth part for a toy construction set.

FIG. 17.1 is a perspective view of a seventeenth part for a toy construction set;

FIG. 17.2 is a left side view of a seventeenth part for a toy construction set;

FIG. 17.3 is a bottom view of a seventeenth part for a toy construction set;

FIG. 17.4 is a rear view of a seventeenth part for a toy construction set;

FIG. 17.5 is a top view of a seventeenth part for a toy construction set;

FIG. 17.6 is a front view of a seventeenth part for a toy construction set;

FIG. 17.7 is a right side view of a seventeenth part for a toy construction set; and

FIG. 17.8 is a perspective view of a seventeenth part for a toy construction set.

FIG. 18.1 is a perspective view of an eighteenth part for a toy construction set;

FIG. 18.2 is a left side view of an eighteenth part for a toy construction set;

FIG. 18.3 is a bottom view of an eighteenth part for a toy construction set;

FIG. 18.4 is a front view of an eighteenth part for a toy construction set;

FIG. 18.5 is a top view of an eighteenth part for a toy construction set;

FIG. 18.6 is a perspective view of an eighteenth part for a toy construction set;

FIG. 18.7 is a rear view of an eighteenth part for a toy construction set; and

FIG. 18.8 is a right side view of an eighteenth part for a toy construction set.

FIG. 19.1 is a perspective view of a nineteenth part for a toy construction set;

FIG. 19.2 is a front view of a nineteenth part for a toy construction set;

FIG. 19.3 is a left side view of a nineteenth part for a toy construction set;

FIG. 19.4 is a rear view of a nineteenth part for a toy construction set;

FIG. 19.5 is a right side view of a nineteenth part for a toy construction set;

FIG. 19.6 is a bottom view of a nineteenth part for a toy construction set;

FIG. 19.7 is a perspective view of a nineteenth part for a toy construction set; and

FIG. 19.8 is a top view of a nineteenth part for a toy construction set.

FIG. 20.1 is a perspective view of a twentieth part for a toy construction set;

FIG. 20.2 is a right side view of a twentieth part for a toy construction set;

FIG. 20.3 is a left side view of a twentieth part for a toy construction set;

FIG. 20.4 is a bottom view of a twentieth part for a toy construction set;

FIG. 20.5 is a rear view of a twentieth part for a toy construction set;

FIG. 20.6 is a front view of a twentieth part for a toy construction set;

FIG. 20.7 is a right side view of a twentieth part for a toy construction set; and

FIG. 20.8 is a perspective view of a twentieth part for a toy construction set.

FIG. 21.1 is a perspective view of a twenty-first part for a toy construction set;

FIG. 21.2 is a top view of a twenty-first part for a toy construction set;

FIG. 21.3 is a bottom view of a twenty-first part for a toy construction set;

FIG. 21.4 is a left side view of a twenty-first construction unit;

FIG. 21.5 is a rear view of a twenty-first part for a toy construction set;

FIG. 21.6 is a front view of a twenty-first part for a toy construction set;

FIG. 21.7 is a right side view of a twenty-first construct part for a toy construction set; and

FIG. 21.8 is a perspective view of a twenty-first part for a toy construction set.

FIG. 22.1 is a perspective view of a twenty-second part for a toy construction set;

FIG. 22.2 is a front view of a twenty-second part for a toy construction set;

FIG. 22.3 is a top view of a twenty-second part for a toy construction set;

FIG. 22.4 is a left side view of a twenty-second part for a toy construction set;

FIG. 22.5 is a perspective view of a twenty-second part for a toy construction set;

FIG. 22.6 is a rear view of a twenty-second part for a toy construction set;

FIG. 22.7 is a bottom view of a twenty-second part for a toy construction set; and

FIG. 22.8 is a right side view of a twenty-second part for a toy construction set.

FIG. 23.1 is a perspective view of a twenty-third part for a toy construction set;

FIG. 23.2 is a left side view of a twenty-third part for a toy construction set;

FIG. 23.3 is a top view of a twenty-third part for a toy construction set;

FIG. 23.4 is a bottom view of a twenty-third part for a toy construction set;

FIG. 23.5 is a right side view of a twenty-third part for a toy construction set;

FIG. 23.6 is a rear view of a twenty-third part for a toy construction set;

FIG. 23.7 is a perspective view of a twenty-third part for a toy construction set; and

FIG. 23.8 is a perspective view of a twenty-third part for a toy construction set.

FIG. 24.1 is a perspective view of a twenty-fourth part for a toy construction set;

FIG. 24.2 is a top view of a twenty-fourth part for a toy construction set;

FIG. 24.3 is a right side view of a twenty-fourth part for a toy construction set;

FIG. 24.4 is a rear view of a twenty-fourth part for a toy construction set;

FIG. 24.5 is a bottom view of a twenty-fourth part for a toy construction set;

FIG. 24.6 is a front view of a twenty-fourth part for a toy construction set;

FIG. 24.7 is a left side view of a twenty-fourth part for a toy construction set; and

FIG. 24.8 is a perspective view of a twenty-fourth part for a toy construction set.

FIG. 25.1 is a perspective view of a twenty-fifth part for a toy construction set;

FIG. 25.2 is a top view of a twenty-fifth part for a toy construction set;

FIG. 25.3 is a right side view of a twenty-fifth part for a toy construction set;

FIG. 25.4 is a rear view of a twenty-fifth part for a toy construction set;

FIG. 25.5 is a bottom view of a twenty-fifth part for a toy construction set;

FIG. 25.6 is a front view of a twenty-fifth part for a toy construction set;

FIG. 25.7 is a left side view of a twenty-fifth part for a toy construction set; and

FIG. 25.8 is a perspective view of a twenty-fifth part for a toy construction set.

FIG. 26 is a side view of a twenty-sixth part for a toy construction set.

FIG. 27 is a side view of a twenty-seventh part for a toy construction set.

FIG. 28 is a side view of a twenty-eighth part for a toy construction set.

FIG. 29 is a side view of a twenty-ninth part for a toy construction set.

FIG. 30 is a side view of a thirtieth part for a toy construction set.

FIG. 31 is a side view of a thirty-first part for a toy construction set.

FIG. 32 is a side view of a thirty-second part for a toy construction set.

FIG. 33 is a side view of a thirty-third part for a toy construction set.

FIG. 34 is a side view of a thirty-fourth part for a toy construction set.

FIG. 35 is a side view of a thirty-fifth part for a toy construction set.

FIG. 36 is a side view of a thirty-sixth part for a toy construction set.

FIG. 37 is a side view of a thirty-seventh part for a toy construction set.

FIG. 38 is a side view of a thirty-eighth part for a toy construction set.

FIG. 39 is a side view of a thirty-ninth part for a toy construction set.

FIG. 40 is a side view of a fortieth part for a toy construction set.

FIG. 41 is a side view of a forty-first part for a toy construction set.

FIG. 42 is a side view of a forty-second part for a toy construction set.

FIG. 43 is a side view of a forty-third part for a toy construction set.

FIG. 44 is a side view of a forty-fourth part for a toy construction set.

FIG. 45 is a side view of a forty-fifth part for a toy construction set.

FIG. 46 is a side view of a forty-sixth part for a toy construction set.

FIG. 47 is a side view of a forty-seventh part for a toy construction set.

FIG. 48 is a side view of a forty-eighth part for a toy construction set.
